UNITED STATES PATENT OFFICE

131,256

DESIGN FOR A DISPLAY BOARD OR THE LIKE

John Bascom Dey, Lynchburg, Va.

Application May 22, 1941, Serial No. 101,095

Term of patent 14 years

To all whom it may concern:

Be it known that I, John Bascom Dey, a citizen of the United States, residing in Lynchburg, in the county of Campbell and State of Virginia, have invented a new, original, and ornamental Design for a Display Board or the Like, of which the following is a specification, reference being had to the accompanying drawing, forming part thereof, in which:

The essential and characteristic features of my design consist in the portions shown in full lines on the drawing.

I claim:

The ornamental design for a display board or the like, substantially as shown and described.

JOHN BASCOM DEY.
